MOUTHPIECE FOR SMOKING PIPES

John Widmer, Rosedale, N. Y.

Application July 29, 1938, Serial No. 222,055

1 Claim. (Cl. 131—210)

This invention relates to mouthpieces for smoking pipes, and has for the primary object the provision of a device of this character which will greatly improve the smoking qualities of a pipe by preventing saliva from the mouth of the smoker from reaching the bowl of the pipe and prevent tobacco juice and particles of tobacco from reaching the mouth of the smoker and which may be readily converted into a cigar or cigarette holder when desired and which will permit several cigarettes to be smoked simultaneously if desired, thereby providing in the device a novelty.

With these and other objects in view, the invention consists in certain novel features of construction, combination and arrangement of parts to be hereinafter more fully described and claimed.

For a complete understanding of my invention, reference is to be had to the following description and accompanying drawing, in which

Figure 1 is a side elevation illustrating a smoking pipe equipped with a mouthpiece constructed in accordance with my invention.

Figure 2 is a vertical sectional view illustrating the mouthpiece.

Figure 3 is a vertical sectional view illustrating the mouthpiece converted to accommodate a cigarette.

Figure 4 is a view similar to Figure 3 showing the device converted to hold a cigar.

Figure 5 is a fragmentary vertical sectional view showing the device converted into a novelty to permit several cigarettes to be smoked simultaneously.

Referring in detail to the drawing, the numeral 5 indicates a stem of a smoking pipe and 6 the bowl of said pipe. The present invention is indicated in entirety by the character 7 and consists of a mouthpiece having a smoke passage 8 therethrough. One end of the smoke passage terminates in a chamber 9 which opens outwardly through one end of the mouthpiece. The chamber 8 receives a fitting or plug 10 which has frictional contact with the walls of the chamber or may be threaded in the chamber if desired and includes a reduced tapered portion 11 adapted for insertion in the stem 5 of the pipe to establish a detachable connection between the mouthpiece and the stem of the pipe. It is to be understood that the fitting 10 has a smoke passage extending from end to end thereof and fitted in one end of the smoke passage is a rod-like member 12 adapted to enter the bore of the stem 5 and terminates in a ball-shaped end 13.

Spaced baffles 14 are formed on the rod-like member. The peripheries of the baffles come in comparatively close contact with the walls of the bore of the stem 5 when the mouthpiece is adapted thereto. Due to the close relation of the 5 peripheries of the baffles with the walls of the bore of the stem 5 they will intercept passing of particles of tobacco from the bowl through the mouthpiece to the mouth of the smoker still permitting a flow of smoke thereby. The rod-like member 12 has smoke grooves formed therein as clearly shown in the drawing.

A filtering element 15 is arranged in the chamber 9 for the purpose of intercepting saliva from the mouth of the smoker and preventing the 15 same from reaching the bowl 6 of the pipe. The filtering element 15 may be constructed of any material suitable for the purpose and is easily removed when saturated so that it can be substituted by another filter of a like construction.

The mouthpiece is provided with oppositely arranged ports 16 in communication with the chamber 9 and open outwardly through opposite sides of the mouthpiece. The ports 16 are 25 normally closed by a ferrule or sleeve 17 removably mounted on the mouthpiece.

If at any time it is desired to use the mouthpiece as a novelty, as shown in Figure 5, the fitting 10 is removed and also the filtering element 15 and also the sleeve or ferrule 17. Several cigarettes may then be positioned to enter the chamber 9, as shown in Figure 5. A pair of cigarettes will be opposed to each other by being inserted in the chamber 9 by way of the 30 ports 16 while another cigarette may be inserted in the chamber endwise of the mouthpiece. The cigarettes thus assembled in the mouthpiece will permit smoking of said cigarettes simultaneously.

Whenever it is desired to smoke a cigarette singly the ferrule or sleeve 17 is repositioned on the mouthpiece to close the ports 16 and the single cigarette is then positioned in the chamber 9, as shown in Figure 3.

To adapt the mouthpiece as a holder for cigars, a ferrule or sleeve 18 is provided on the mouthpiece which extends beyond the open end of the chamber so as to receive therein an end of a cigar, as shown in Figure 4, with said end of the cigar partially entering the chamber 9. When the mouthpiece is employed as a holder for cigarettes or cigars, the filter 15 may be employed if desired. It is to be seen that the 55

sleeve or ferrule 18 will close the ports 16 when the device is acting as a holder for a cigar.

It is believed that the foregoing description, when taken in connection with the drawing, will 5 fully set forth the construction and advantages of this invention to those skilled in the art to which such a device relates, so that further detailed description will not be required.

What I claim is:

10 A device of the character set forth comprising a mouthpiece having a smoke passage and a chamber opening outwardly through one end thereof and in communication with said smoke passage, a fitting removably mounted in said

chamber and extending outwardly therefrom to frictionally fit in a bore of a stem of a pipe and having a smoke passage therethrough, a rod-like member fitted in the passage of said fitting and terminating in a ball-shaped end 5 within the stem of the pipe, and baffle discs formed on said rod in spaced relation and each having a notch and arranged between said fitting and the ball-shaped end of the rod-like member, said notches of the discs being arranged in alignment to permit smoke to pass the baffle discs.

JOHN WIDMER.
